(57) CLAIM

The ornamental design for an insulin pump case, as shown and described.

DESCRIPTION

FIG. 1 is a top and side perspective view of a leather insulin pump case, shown with the cover flap partially open.

FIG. 2 is a top perspective view thereof, shown with the cover flap fully open; and,

FIG. 3 is a rear perspective view thereof, shown with the cover flap fully open.

The broken lines in the figures depict stitching on the article that forms part of the claimed design.
